(57) **CLAIM**

The ornamental design for a hair roller, as shown and described.

DESCRIPTION

FIG. 1 is a top and side perspective view of the hair roller showing my new design;
FIG. 2 is an end elevational view thereof;
FIG. 3 is an elevational view of the opposite side of FIG. 1;
FIG. 4 is a top plan view thereof; and,
FIG. 5 is a bottom plan view thereof.
The interior portions of the roller design form no part of the invention.
